(57) **CLAIM**

The ornamental design for an electrosurgical controller, as shown and described.

DESCRIPTION

FIG. 1 is a perspective view of the electrosurgical controller; FIG. 2 is an overhead view of the electrosurgical controller; FIG. 3 is a side elevation view of the electrosurgical controller;

FIG. 4 is a side elevation view of the electrosurgical controller; and,

FIG. 5 is a front elevation view of the electrosurgical controller.

The portions of the electrosurgical controller depicted in broken lines form no part of the claimed design.
